(57) **CLAIM**

The ornamental design for a shroud for mounting accessories to firearms, as shown and described.

DESCRIPTION

FIG. 1 is a top front right perspective view of a shroud for mounting accessories to firearms, showing my design;
FIG. 2 is a bottom front right perspective view thereof;
FIG. 3 is a right-side elevation view thereof, the left-side elevation view being a mirror image thereof;
FIG. 4 is a rear elevation view thereof;
FIG. 5 is a front elevation view thereof;
FIG. 6 is a top plan view thereof; and,
FIG. 7 is a bottom plan view thereof.

The broken lines shown in the drawings depict the bounds of the shroud for mounting accessories to firearms that form no part of the claimed design.
